United States Patent Office

Des. 178,443
Patented July 31, 1956

178,443

COMBINED PRICE CALCULATOR AND DISPLAY DEVICE

Lawrence S. Wilcoxon, Cincinnati, Ohio, assignor to The Brunhoff Manufacturing Company, Cincinnati, Ohio, a corporation of Ohio

Application February 13, 1956, Serial No. 40,132

Term of patent 14 years

(Cl. D80—1)

FIG. 2.

FIG. 1.

FIG. 3.

FIG. 4.

FIG. 5.

Figure 1 is a side elevational view of a combined price calculator and display device showing my new design.

Figure 2 is a rear elevational view of the device.

Figure 3 is a plan view of the device.

Figure 4 is a front elevational view of reduced scale illustrating the device.

Figure 5 is a perspective view of the device.

I claim:

The ornamental design for a combined price calculator and display device, as shown.
